UNITED STATES PATENT OFFICE.

WILLIAM F. LAUTENSCHLAGER, OF CINCINNATI, OHIO, ASSIGNOR TO LORENZ MUTHER,
OF DENVER, COLORADO.

EYELETING-MACHINE.

933,315.

Specification of Letters Patent. Patented Sept. 7, 1909.

Application filed August 12, 1908. Serial No. 448,195.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Eyeleting-Machines, of which the following is a specification.

Eyeleting machines for setting eyelets automatically are in practice operated at a high rate of speed, the eyelets being usually set at the rate of two hundred and fifty to four hundred per minute. The range of work in the usual shoe factory where these machines are employed is also great, both in regard to the size of eyelets employed and the distance apart at which the eyelets are set in the stock. In order to accommodate the necessary range of work, and to provide the necessary speed of operation for given eyelets or spacing-distances between eyelets, it has been a general practice heretofore, in factories employing machines of this character, to install machines of different sizes for different ranges of work or sizes of eyelets, these machines being usually installed in sets of three. The work or stock, passing through the various departments of the factory for having successive operations imposed to it, reaches the eyeleting department in lots, the several lots being intended to receive eyelets of various sizes, also spaced different distances apart. For economical operation it has been the practice heretofore to provide each operator with a set of eyeleting machines above mentioned, usually three, so that entire lots could be completed without the necessity of breaking or dividing the lots, the consequence being that the operator was obliged to do part of the eyeleting on one machine and other parts on the other machines of the set, the space in the shop occupied by each operator being the sum of the space occupied by the several machines of his set of machines.

It is the object of my invention to provide an eyeleting machine capable of setting eyelets of the various sizes usually employed in eyeleting work, and capable of a wide range of feeding movement for accommodating the various requirements of spacing-distance between eyelets, while permitting very rapid operation for all sizes and spacing-distances between eyelets.

It is the object of my invention further to increase the speed of operation of machines of this character, and further to dispense with the necessity of employment of sets of eyeleting machines hereinbefore mentioned and to provide a machine capable of performing the work of the several machines of the set of machines at a very high rate of speed, thereby saving the cost of extra machines, reducing the space occupied by the operator, and permitting the operator to set the eyelets of various sizes at differently-spaced distances without leaving his position.

I accomplish these objects by novel mechanism.

The invention will be readily understood from the following description and claims, and from the drawings, in which latter:

Figure 1 is a front elevation of my improved device. Fig. 2 is a vertical section of the same on the line $x-x$ of Fig. 1. Fig. 3 is a vertical cross-section of the same on a line corresponding to the line $y-y$ of Fig. 2. Fig. 4 is a detail in edge elevation showing the means for positioning the bell-crank lever; and, Fig. 5 is a detail in section on the line $z-z$ of Fig. 2 showing the adjustment in the rocking-member.

1 represents the frame of the machine, in which a cam-shaft 2 is journaled in bearings 3.

4 is a head supporting a punch-ram 5. Sidewise reciprocation is imparted to the head, as by having bearings 6 thereon slide sidewardly on a rod 7 secured to the frame and a rod 8, secured to the head, sliding sidewardly in bearings 9 of the frame, the sidewise reciprocation being imparted by means to be presently described. The punch-ram has up and down reciprocation imparted to it by a crank-pin 10 journaled in a block 11 operating in a slide-way 12 in the punch-ram, the crank-pin being on a rock-shaft 13 which has a segment-gear 14 thereon.

15 is a lever pivoted on screws 16 in the frame and having a cam-housing 17 in which a cam 18 on the cam-shaft operates for imparting sidewise oscillation to said lever, the upper end of said lever having a segment-gear 19 meshing with the segment-gear 14 for imparting rocking motion to said rock-shaft 13.

20 is a lower setting-die adapted to coöp-

erate with the upper setting die 21 on the punch-ram, the latter having a setting-face and also acting as a punch in manner to be hereinafter described. These setting dies 5 are removable for substituting other setting-dies of various sizes for accommodating eyelets of different sizes. The lower setting-die is on a ram 22 which has up and down reciprocation in bearings 23 in the 10 frame, these reciprocations being imparted by a crank-pin 24 on the cam-shaft journaled in a slide-block 25 in a guide-way 26 on the lower setting-ram.

There is an eyelet-receiving finger 27 15 adapted to receive eyelets from an eyelet-chute 28 which has movement imparted thereto by means of an angle-lever 29 articulated therewith and operated by the cam 30 on the cam-shaft rotating in a cam-housing 31 on said angle-lever. The eyelet-finger is normally pressed upwardly by a spring 32 but is adapted to be retracted by the punch-die when the eyelet is being set.

Cross feed is imparted to the punch-head. 25 The punching operation takes place at one of the limits of movement of said punch-head, and the setting operation takes place at the other of its limits of movement. My improved device provides means whereby 30 these limits of movement may be separated small or great distances for accommodating all classes of work and sizes of eyelets ordinarily used. The distance between the said 35 limits of movement represents the spacing distance between eyelets.

The punch is adapted to descend on the anvil 33 for performing the punching operation, which takes place at the right hand limit of movement of said punch-ram illustrated in Fig. 1, the punch descending for 40 performing the punching operation and then moving to the left into line with the lower setting-die, carrying the stock with it, at which point the eyelet, heretofore received 45 upon the eyelet-finger, is set into the stock, whereupon the setting dies again separate, the punch being returned to its punching position for repeating the operation.

In order to obtain a wide range of side- 50 wise reciprocation of the punch-head I have provided a cam-housing 34 which has a guideway 35 therein preferably received about and guided by the cam-shaft, and is provided with an extension 36 having a 55 guideway 37 therein, in which latter a guide-block 38, shown as on one of the screws 16, is received. A cam 39 is on the cam-shaft and operates on the upper contact-face 40 and the lower contact-face 41 of 60 the cam-housing for moving said cam-housing radially of said cam-shaft, the said guide-ways maintaining said movement in a given direction, the movement being exemplified as a vertical movement. A rocking 65 member 42 is journaled about the rock-shaft

13. It comprises a sleeve 43 and a finger 44, having a hub 45 encompassing the sleeve, the finger and sleeve being relatively adjustable by set-screws 46. There is a slot 47 in the finger in which there is a slide-block 48, a pin 49 in the head being journaled in the slide-block, the construction translating the rocking movement of the rocking-member into sidewise reciprocating movement of the head. The rocking-member 70 is provided with an arm 50 in which there is an arc-slot 51 receiving a block 52 arranged to have sliding movement therein. 75 53 is a connecting-rod which is pivoted at 54 to said block and at 55 to the upward 80 extension on said cam-housing. The arc of the slot 51 is described from the pivotal axis of the connecting-rod 53 with the cam-housing 34, whereby I obtain an arc of short 85 radius compared with the distance between the rotary axis of the cam-shaft and the pivot 54. The said arc is exemplified as described from said pivotal axis when said setting-dies are in opposition or setting position, in other words, at the setting limits of 90 movement of said punch-ram, and when said cam-housing is at its upward limit of movement, as shown in Fig. 3. The block 52 is shiftable in the slot 51 toward and 95 from the rocking axis of the rocking-member. The nearer this block, that is to say, the articulation at the outer end of the connecting-rod 53, is to the rocking axis of said rocking-member, the greater will be the 100 rocking movement imparted to the rocking-member by the cam 39 through the radially moving cam-housing and the connecting-rod articulated to the latter and to said rocking-member.

56 is a bell-crank lever pivoted at 57 to the frame. A link 58 is articulated with the arm 59 of said lever at 60 and with said connecting rod at 61. Means are provided for adjusting the range of movement of the bell-crank lever. Thus it is received in a 105 slot 62, the walls 63 of which are provided with perforations 64 for receiving pins 65 66 against which the arm 67 of the bell-crank lever is arranged to strike for controlling the pivotal position of said bell-crank 110 lever and thereby controlling the range of cross-reciprocation of the punch. In the exemplification, the higher the arm 67 is positioned the smaller will be the cross-reciprocation of the punch, and the lower the position of said arm is the greater will be this 115 cross-reciprocation. The positioning effect of the bell-crank lever upon the connecting-rod is produced from a pivotal point which always moves in a given direction radially 120 of the cam-shaft and upon an arc having a short radius compared with the distance from the rotary axis of the cam-shaft to the arc-slot, the resultant of which is an increased 125 distance of cross-reciprocation of 130

the punch-head, by which I am enabled to provide adjustments of lengths of cross-reciprocation accomplishing spacing-distances between eyelets throughout a range which 5 will encompass the spacing-distances employed in ordinary practice and which range heretofore had to be accomplished by a plurality of machines as hereinbefore stated.

The eyelets in the quarters of a shoe are 10 usually set at different distances apart, the eyelets at the bases of the quarters being closer together than those at the tops of the quarters. In setting the eyelets those of one spacing on the quarter are first set and the 15 machine then changed by swinging the bell-crank lever while running for setting the eyelets of the other spacing on that quarter. The arm 67 is normally at its upward limit, being held in place by a spring 68.

20 69 is a rock-shaft which has a projection 70 thereon between which and the bell-crank lever there is a connecting-link 71, the spring 68 being between said projection and a bracket 72, on which the spacing walls 63 are 25 located. The rock-shaft 69 also has a projection 73 with which a link 74 connects, the link leading to a suitable treadle.

By means of my improved device the 30 opposing movements of the setting dies are also accomplished at a definite point with relation to the cross-reciprocation of the punch-head. Thus the arrow 75 represents the direction of rotation of the cam-shaft. The cam-housing 34 always moves in the 35 same plane radially of the cam-shaft, the approach of the setting-dies taking place at one of the limits of cross-reciprocation of the punch-head effected by the movement of said cam-housing. The cam-housing always 40 moving in the same direction, will always have its contact-faces engaged by the high point of the cam 39 at the same point in the rotation of the cam throughout all adjustments for lengths of cross-reciprocation of the 45 punch-head, so that a definite time-relation is maintained between the rocking of the rock-shaft 13 and of the rocking-member 42 in all such adjustments, whereby I am enabled to leave a material part of the factor 50 of safety between the timing of said two motions out of consideration, and to correspondingly increase the speed of the machine.

The connecting-rod 53 may be adjustable 55 to length and may comprise the end-pieces 76 77 and the rod 78, the latter having right and left hand threads at its respective ends for being received in similarly threaded sockets in said end-pieces, jam-nuts 79 se- 60 curing the parts of the connecting-rod in rigid relation.

Having thus fully described my invention, what I claim as new and desire to secure by Letters Patent is:

65 1. In an eyeleting machine, the combina-

tion of a punch-head, a rocking-member articulated therewith for translating the rocking motion of said rocking-member into side- 70 wise reciprocating motion of said punch-head, said rocking-member being provided with an arm, a cam-shaft, a cam-housing reciprocated thereby, a connection-rod articulated with said cam-housing and arm, the articulation of said connecting-rod with 75 said arm being adjustable toward and from the rocking axis of said rocking-member, and means for maintaining the reciprocation of said cam-housing in a given direction, with said connecting-rod extending at different angles to said given direction of reciprocation of said cam-housing for different 80 adjustments of said articulation of said connecting-rod with said arm.

2. In an eyeleting machine, the combination of a punch-head having sidewise reciprocation, a punch-ram having up and down reciprocation on said head, a rock-shaft having articulation with said punch-ram, a rocking-member having articulation with said head, said rock-shaft and rocking member having common rocking axes, a cam and cam-housing therefor having operative connection with said rock-shaft for rocking said rock-shaft, a second cam, a second cam-housing operated by said second cam, said 95 rocking-member provided with an arm, a connecting-rod having articulation with said second-named cam-housing and said arm, said articulation between said connecting-rod and arm being adjustable toward and 100 from said common rocking axes, and means for maintaining the reciprocation of said cam-housing in a given direction while permitting lateral movement of said articulation between said connecting-rod and arm, 105 and constructed and arranged for maintaining definite relation between the reciprocations of said head and said punch-ram, substantially as described.

3. In an eyeleting machine, the combination of a pair of setting-dies one of said setting-dies comprising a punch, a ram for the latter, a head for said ram, a rock-shaft having connection with said ram for translating the rocking motion of said rock-shaft into up and down reciprocation of said punch-ram, a rocking-member having connection with said head for translating the rocking motion of said rocking-member into sidewise reciprocation of said head, said rock-shaft and rocking-member having common rocking axes, said rocking-member having an arm, means for rocking said rock-shaft, a cam-shaft provided with a cam, a cam-housing therefor having an extension 115 extending toward said rocking-member, a connecting-rod articulated with said extension adjacent its point of nearest approach to said rocking-member, and adjustable connection between said connecting-rod and arm 120 125 130

- adjustable on an arc described from said articulation between said extension and said link as a center when said setting-dies are in juxtaposition, and guiding means for 5 maintaining said cam-housing in a given direction of movement toward and from said rocking-member throughout the adjustments of said adjustable connection, substantially as described.
- 10 4. In an eyeleting machine, the combination of a punch-ram, a head for the same, a rocking-member for imparting reciprocation to said head, means for imparting reciprocation to said punch-ram transverse to said 15 last-named reciprocation, a housing, a shaft having means thereon for reciprocating said housing toward and from said rocking-member, guiding means for maintaining said housing in a given path of reciprocating 20 movement, a connecting-rod having articulation with said housing, said articulation being distanced from said last-named shaft and located between said last-named shaft and rocking-member, said connecting-rod 25 having articulation with said rocking-member adjustable toward and from the rocking axis of said rocking-member, and means for controlling the position of said last-named articulation.
- 30 5. In an eyeleting machine, the combination of a pair of setting-dies embracing a punch, a ram for the latter, a head on which said ram has up and down reciprocation, a rocking-member having an arm, a housing 35 having reciprocation toward and from said rocking-member, a shaft and means thereon for imparting said reciprocation to said housing, guiding means for maintaining said housing in a given path of reciprocating 40 movement, a connecting-rod having articulation with said housing and extending in directions at angles to said given path of reciprocating movement, said articulation being distanced from said shaft and located between 45 said shaft and rocking-member, said connecting-rod having articulation with said arm, said last-named articulation being adjustable lengthwise of said arm on an arc described from said articulation between said 50 connecting-rod and housing when said punching-dies are in juxtaposition, a bell-crank lever and a link therefor articulated to said bell-crank lever and to said connecting-rod for controlling the position of said articula-
- tion between said connecting-rod and arm, 55 substantially as described.
6. In an eyeleting machine, the combination of a head arranged for having a setting-die thereon, a rocking-member articulated therewith for translating the rocking motion 60 of said rocking-member into sidewise reciprocating motion of said head, said rocking-member being provided with an arm, a cam-shaft, a cam-housing reciprocated thereby, a connecting-rod articulated with said cam-housing and arm, the articulation of said connecting-rod with said arm being adjustable toward and from the rocking axis of 65 said rocking-member, guiding means for said cam-housing for maintaining said cam-housing in a given path of reciprocating movement irrespective of adjustment of said last-named articulation, and so constructed and arranged that a straight line drawn between the pivotal axes of said articulations of said 70 connecting-rod with said cam-housing and arm is at an angle to the path of reciprocating movement of said cam-housing, for the purpose specified.
7. In an eyeleting machine, the combination of opposing setting-dies, a head having sidewise reciprocation, a ram having up and down reciprocation on said head and having one of said setting-dies thereon, means for reciprocating said ram, a rocking-member 75 having articulation with said head, a cam-housing, a cam therefor, means for guiding said cam-housing in a given straight path of reciprocating movement, a connecting-rod having articulation with said cam-housing 80 between said cam and rocking-member, said connecting-rod having articulation with said rocking-member which is adjustable on an arc described from the axis of articulation 85 between said connecting-rod and cam-housing 90 when said setting does are in setting relation, for maintaining said cam and cam-housing in similar relation to said setting-dies throughout the adjustments of the articulation between said connecting-rod and rocking-member, 95 for the purpose specified.
- In testimony whereof I have subscribed my name hereto in the presence of two subscribing witnesses.
